NUMBERING DEVICE FOR PHOTO-PRINTING MACHINES

Joseph L. Barber, Greeley, Colo.

Application September 5, 1931, Serial No. 561,399

15 Claims. (Cl. 101—78)

This invention relates to a device for numbering printing papers which are placed over negatives in a photo-printing machine during the photo-printing operations thereof. In practice, 5 variable numbers of photographs are made from each of negatives inserted in a photo-printing machine, printing papers being successively placed over a negative for repeated photo-printing operations, and it is desirable to mark the 10 printing paper or printing papers placed over a negative with a distinctive number, figure, or character, to thus identify the resultant photograph or group of photographs made from each negative.

15 An object of the present invention is to provide a numbering device adapted to be associated with a photo-printing machine in such manner as to cause a printing paper situated in printing position over a negative in said machine to be stamped or impressed with a predetermined number, figure, or character when the platen of said machine is depressed or lowered to printing position.

A further object is to provide a numbering device adapted to be associated with the platen of a photo-printing machine to be operative each time said platen is depressed or lowered to printing position to cause a printing paper situated over a negative in said machine to be stamped or impressed with a number, figure, or character which it was before predetermined said printing paper should receive, whereby to identify the resultant photograph or group of photographs made from a negative and thus render said photograph or group of photographs more readily and easily distinguishable from photographs made from all other negatives operated upon in the machine.

A still further object is to provide a numbering device as just stated, wherein will be incorporated various novel and improved features and characteristics of construction.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

Fig. 1 is a side elevational view of a numbering device for photo-printing machines made according to the invention and shown as when applied to use upon a photo-printing machine, the platen of said machine being disclosed in elevated or up position;

Fig. 2 is a view partially in side elevation and partially in vertical section of the numbering device and the portion of the photo-printing machine shown in Fig. 1, the platen of said machine being disclosed in depressed or down position;

Fig. 3 is a transverse sectional view detailing the manner of mounting the supporting or printing arm for the numbering element upon the platen of the photo-printing machine;

Fig. 4 is a transverse sectional view detailing said numbering element and a manner of mounting the numbering element upon said supporting or printing arm;

Fig. 5 is a horizontal sectional view taken substantially as on line 5—5 in Fig. 2; and

Fig. 6 is a view in vertical section substantially corresponding with the disclosure of Fig. 2, but showing the numbering device disconnected to thus be inoperative.

With respect to the drawings and the numerals of reference thereon, 10 represents a fragment of a photo-printing machine including the usual window 11 with glass covering 12, and 13 designates the platen of said photo-printing machine which is pivotally supported, as at 14, upon a suitable bracket 15 conveniently attached to the top or table of said machine. In Fig. 1 the platen is shown in elevated or non-printing position, and in Fig. 2 said platen is shown in depressed or printing position, means, designated generally at 16, mounted upon an upright 17 carried by said machine and pivotally attached to an intermediate portion of the platen as at 18, being for the purpose of manipulating said platen between its positions as in Figs. 1 and 2 in a manner not necessary to be herein set forth. Suffice it to say, that when a photograph is to be printed, the platen is automatically moved from non-printing position as in Fig. 1 to printing position as in Fig. 2; directly over the glass 12, to there remain for the predetermined interval a printing paper is to be exposed to the negative, and is then automatically returned to non-printing position as in said Fig. 1. Numeral 19 represents a negative placed over the glass 12 in position to be operated upon, and 20 denotes a printing paper which has been suitably laid over said negative. It will

be understood that printing papers, such as 20, are successively laid over a negative, such as 19, for repeated photo-printing operations performed upon a negative to the production of a desired 5 number of photographs from said negative, a single photo-printing operation being performed each time the platen is depressed or lowered to printing position in the manner as described.

The improved numbering device is assembled 10 with the photo-printing machine to be operative each time the platen thereof is moved to printing position to cause a printing paper situated over a negative in said machine to be stamped or impressed with a number, figure, or character 15 which it was before predetermined said printing paper should receive, to thus furnish the printing paper with a mark for identifying the resultant photograph or group of photographs made from a negative, thereby making said photograph or 20 group of photographs readily and easily and unmistakably distinguishable from photographs printed from other negatives placed in the machine.

A numbering element, denoted generally at 21, 25 is suitably carried, as at 22, upon a supporting or printing arm 23 therefor, said supporting or printing arm having its end portion which is spaced from said numbering element attached, as at 24, to a U-shape bracket 25 the downturned 30 flanges 26 of which are supported upon a double headed pivot pin 27 and between spaced apart ears 28 extending upwardly from an intermediate portion of the platen 13, in which said spaced apart ears 28 said double headed pivot pin 27 is mounted. The supporting or printing arm 23 extends longitudinally of the platen 13, and the outer end portion of said supporting or printing arm, which carries the numbering element 21, is disposed directly above a cut-out portion 29 through the adjacent end of said platen adapted 35 to receive said numbering element. A shaped spring element includes a portion 30 coiled about the pivot pin 27, a portion 31 which resiliently engages underneath the lower surface of the end portion of the supporting or printing arm 23 at the side of the pivot pin 27 opposite the numbering element 21, and a portion 32 which resiliently engages a plate 33 fastened down upon the platen between the spaced apart ears 28, as at 40 34, said shaped spring element normally urging said supporting or printing arm 23 in direction to cause the numbering element 21 to engage the printing paper 20, as will be more clear from 45 Figs. 2 and 3.

The numbering element 21 may be of any construction suiting it to its purpose. As shown, said numbering element consists of a frame including aligned rollers 35 at the upper end thereof, a supporting plate 36 at the lower end thereof, and separate sets of rubber bands 37, one for each roller 35, ridable over said rollers and said supporting plate, each of said rollers 35 being separately rotatable and each of said rubber bands including a series of digits, numbers, figures, or characters 38 thereon. It will be apparent that the rubber bands 37 can be manually adjusted to bring any desired number, figure, or character to be stamped or impressed upon a printing paper 20 beneath the supporting plate 36 and opposite said printing paper. Obviously, a numbering element, such as 21, which is automatically adjusted, could be substituted for the numbering element illustrated and described.

An inking roller 39 is rotatably supported, as 75 at 40, upon a carrying arm 41 for said inking

roller, which carrying arm is longitudinally slideable along an upper portion of the platen in a guideway 42 in part supplied by the plate 33, as will be more clear from Fig. 3. The inking roller 39 is disposed in proximity to the numbering element 21, and the adjacent portion of the platen is suitably cut away as shown to provide clearance for said inking roller. The end portion of the inking roller carrying arm 41 opposite the inking roller is pivotally and detachably connected, as at 43, to one end of an upwardly inclined link 44 arranged longitudinally of the platen in inclined relation thereto, the opposite end of which link is pivotally connected, as at 45, to the upper end of a supporting post 46 at the side of the platen axis 14 opposite the numbering element 21, said post as disclosed being removably carried by the bracket 15 and extending upwardly therefrom. The inking roller carrying arm 41 has a cam 47 fixedly attached to its upper surface, which cam is adapted to be ridden by a roller 48 upon a small bracket 49 attached to an intermediate portion of the supporting or printing arm 23 and extending downwardly therefrom.

The arrangement is such that when the platen is in elevated or non-printing position, as shown in Fig. 1, the roller 48 is at distance from the axis 45 to rest upon a high part of the cam 47 as disclosed in said Fig. 1. At this time the inking roller 39 is situated beneath the numbers, figures, or characters 38 adjacent the supporting plate 36. When then the platen is depressed in the manner as already described, said roller 48 moves to a greater distance away from the axis 45, 100 due to the elevation of said axis 45 above the axis 14 for the platen 13, to thus ride off of the cam 47 and cause the numbering element 21 to ride off of the inking roller 39. Upon release of the supporting or printing arm 23 by the cam 47 and the concurrent release of the numbering element 21 by the inking roller 39, the shaped spring element upon the pivot pin 27 causes the working face of said numbering element to engage the printing paper, as disclosed in Fig. 2, to thus stamp or impress the number, figure, or character 105 then positioned beneath the supporting plate 36 upon said printing paper, as will be clear. Thereafter, upon elevation of the platen to again move the roller 48 closer to the axis 45, said roller 48 110 rides inwardly upon the cam 47 to elevate the numbering element from its position as in Fig. 2 to its position as in Fig. 1 and to cause the inking roller 39 to wipe over the working face of the numbering element 21, it being apparent that said inking roller will be partially rotated both when it is coming into engagement with the numbered element and when it is being released therefrom, to thus cause the whole surface of the inking roller to in time be utilized in the supplying of 115 inking or writing fluid to the numbers, figures, or characters of said numbering element. Desirably, when the platen is in elevated or non-printing position and the parts are situated as in Fig. 1, the number, figure, or character of the numbering element which is in position for printing rests directly upon said inking roller as disclosed in said Fig. 1, the inner end of the cam 47 being slightly relieved to the accomplishment 120 of this end.

It may be desirable in some instances to accomplish printing operations in a photo-printing machine with the numbering device assembled with said machine but inoperative. In such event, all that is necessary is to disconnect the 125 130 135 140 145 150

- inking roller carrying arm 41 from the link 44 at the detachable pivot 43, to turn said link on its axis to the position shown in Fig. 6, and to push said carrying arm 41 outwardly so that the 5 cam 47 rides beyond the roller 48 and the inking roller 39 rides under the numbering element 21 to position where said numbering element is supported in elevated position upon an inner portion of said inking roller in about the manner 10 as shown in said Fig. 6. It will be evident that the shaped spring element upon the pivot pin 27 will now exert its force, through the instrumentality of the numbering element, upon the inking roller to firmly retain the parts in the position as disclosed in Fig. 6 and render the numbering device inoperative to stamp or impress printing papers as long as the link 44 and the inking roller carrying arm 41 remain disconnected. 15
- 20 It will be apparent that applicant has produced a numbering device for photo-printing machines consisting of very few parts all quite simply constructed. The efficiency of the device has been amply proven in actual practice, and 25 said device has been found to be very accurate and useful. It is to be observed that should the hand of an operator become accidentally caught under the numbering element of the device, no actual damage can be done because of the fact 30 that said numbering element is spring actuated. Each time the platen is moved from non-printing to printing position, the supporting or printing arm 23 will be gently released to the spring action which accomplishes the printing, and all 35 of the stampings and impressions made upon the printing papers will be uniform and clear for the reason that the actual printing is accomplished by said spring action, which, naturally, is precisely the same each time said platen is 40 depressed.
- What I claim is:
1. The combination with a photo-printing machine including a pivotally supported platen swingable to printing and non-printing positions 45 relatively to a printing paper arranged over a negative situated in printing position in said machine, of an element for placing an identifying mark upon said printing paper, a carrying arm for said element pivotally mounted upon said platen, a roller supported by said carrying arm, a member longitudinally slidable along said platen and carrying a cam adapted to engage said roller when said platen is swung from printing to non-printing position to swing said arm upon its 50 axis in direction away from said printing paper, resilient means operative upon said carrying arm when said platen is swung from non-printing to printing position to swing said arm upon its axis in direction toward said printing paper, to thus 55 cause said element to engage said printing paper, and a marking fluid supplying roller attached to said member slidable along said platen adapted to engage said element when said platen is in non-printing position and to be clear of said element when said platen is in printing position. 60
  2. The combination as specified in claim 1, a link having one of its ends pivoted to said slidable member, said link extending longitudinally of said platen in inclined relation thereto, and a pivotal support for the other end of said link at the side of the axis of said platen opposite said element and above the elevation of said platen axis. 65
  3. The combination as specified in claim 1, a link detachably pivoted to said slidable member 70
- and extending longitudinally of said platen in inclined relation thereto, and a pivotal support for said link at the side of the axis of said platen opposite said element and above the elevation of said platen axis. 75
4. The combination with a photo-printing machine including a platen movable about an axis to printing and non-printing positions relatively to a printing paper arranged over a negative situated in printing position in said machine, of a device for placing an identifying mark upon said printing paper, an arm carrying said device and movable about an axis parallel to said axis, a cam on said platen, means on said arm for engaging said cam operative when the platen is moved from printing to non-printing position for moving said element to a receded position, resilient means operative to move said element to position to engage said printing paper when said platen is moved from non-printing to printing position, and marking fluid supplying means adapted to engage said element when in receded position and to be clear thereof when in engagement with said printing paper. 80
5. The combination with a photo-printing machine including a platen movable about an axis to printing and non-printing positions relatively to a printing paper arranged over a negative situated in printing position in said machine, of an element for placing an identifying mark upon said printing paper; means carrying said element swingable about an axis parallel to said axis including a resilient member, and a cam on said platen for engaging said carrying means for tensioning said resilient member when said platen 100 is moved from printing to non-printing position for moving said element to a receded position, said resilient member being adapted to operate to move said element to position engaging said printing paper when said platen is moved from 105 non-printing to printing position. 110
6. The combination with a photo-printing machine including a platen movable about an axis to printing and non-printing positions relatively to a printing paper arranged over a negative situated in printing position in said machine, of a device for placing an identifying mark upon said printing paper, an arm carrying said device and swingable about an axis parallel to said axis, resilient means operative upon said carrying means 120 to move said device to engaging relation with said printing paper when said platen is moved from non-printing to printing position, and means carried by said platen operative upon said arm and against the action of said resilient means when 125 said platen is moved from printing to non-printing position for moving said device to a receded position. 130
7. The combination with a photo-printing machine including a platen movable about an axis to printing and non-printing positions relatively to a printing paper arranged over a negative situated in printing position in said machine, of a device for placing an identifying mark upon said printing paper, resilient means operative upon 135 said device to cause the same to engage said printing paper when said platen is moved from non-printing to printing position, an arm carrying said device and swingable about an axis parallel to said axis and means on said platen 140 operative upon said element and against the action of said resilient means when said platen is moved from printing to non-printing position for moving said element to a receded position. 145
8. A photo-printing machine having in com- 150

- bination, a platen movable to printing and non-printing positions for engaging a print, a device for placing an identifying mark upon said print, means operative to move said device to position 5 to engage said print when said platen is moved to printing position, a cam on said platen, an arm mounted on said platen and carrying said device having means engaging said cam, and means for moving said cam as said platen is swung to non-printing position to cause the same to engage said last mentioned means and move said device to inoperative position. 10
9. A photo-printing machine having in combination, a platen swingable about an axis to and from printing position to engage a print, an arm carried by said platen and pivoted to swing about an axis parallel to said axis, a numbering device carried by said arm, a cam carried by said platen, and means on said arm engaged by said cam to move said device to inoperative position. 15
10. A photo-printing machine having in combination, a platen swingable about an axis to and from printing position adapted to engage a print, an arm pivotally mounted on said platen to swing about an axis parallel to said axis, a numbering device carried by said arm, means tending to swing said numbering device to operative position to engage said print, a cam on said platen and movable relatively thereto, and means on said 20 arm engaged by said cam to move said numbering device to inoperative position. 25
11. A photo-printing machine having in combination, a platen swingable to printing position to engage a print and upwardly to inoperative position, an arm pivotally mounted on said platen, a numbering device carried by said arm for engaging a print, a slide on said platen, a cam on said slide, said arm having means engageable by said cam, a stationary member, and means connecting said slide and stationary member to move said slide to cause engagement of said cam and last mentioned means to move said numbering device to inoperative position. 30
12. A photo-printing machine having in combination, a platen movable to and from printing position to engage a print, an arm pivoted on said platen, a numbering device carried adjacent one end of said arm, resilient means urging said arm and numbering device to operative position to engage a print, a member slidably on said platen, means carried by said member for engaging said arm to move said arm and numbering device to inoperative position, and means independent of said platen connected to said slide for moving the same as said platen is moved. 35
13. A photo-printing machine having in combination, a platen swingable to and from printing position for engaging a print, an arm swingably mounted adjacent one end on a pivot on said platen, a numbering device carried by said arm adjacent its other end, a spring engaging said arm and platen adjacent said pivot to move said numbering device to operative position, a roller on said arm intermediate said device and pivot, a slide mounted on said platen, a cam carried on said slide, and means for moving said slide to cause engaging of said cam and roller to swing said arm and numbering device to inoperative position as said platen moves to inoperative position. 40
14. A photo-printing machine having in combination, a platen movable to and from printing position for engaging a print, an arm pivoted on said platen, a numbering device carried adjacent one end of said arm, resilient means urging said arm and numbering device to operative position to engage a print, a member slidably on said platen, means carried by said member for engaging said arm to move said arm and numbering device to inoperative position, and means independent of said platen connected to said slide for moving the same as said platen is moved. 45
15. The structure set forth in claim 14, said slide having an inking roller carried thereon over which said numbering device moves. 50
